COFFEE MAKER

Max D. Weiss, Rochester, N.Y., assignor to Robeson, Rochester Corporation, Rochester, N.Y., a corporation of New York

Filed Mar. 26, 1962, Ser. No. 69,425

Term of patent 7 years

(Cl. D44—26)

Fig. 2.

Fig. 1.

FIG. 1 is a perspective view of a coffeemaker showing my new design;

FIG. 2 is a top plan view thereof; and

FIG. 3 is a vertical sectional view of the cover along line 3—3 of FIG. 2.

The dominant features of the coffeemaker are shown in solid lines.

I claim:

The ornamental design for a coffeemaker, substantially as shown and described.
